UNITED STATES PATENT OFFICE.

WILLIAM N. CROPPER, OF LEXINGTON, KENTUCKY.

SCREEN.

Application filed January 8, 1925. Serial No. 1,234.

To all whom it may concern:

Be it known that I, WILLIAM N. CROPPER, a citizen of the United States of America, residing at Lexington, in the county of Fayette and State of Kentucky, have invented certain new and useful Improvements in Screens, of which the following is a specification.

My invention relates to improvements in 10 screens and screen construction.

An important object of my invention is to provide a screen with new and improved means for allowing ready removal or replacement of the netting.

15 Another object of my invention is the provision of a device of the above mentioned character with a key member for locking the netting keepers in position.

Another object of my invention is to provide 20 a device of this character with improved means for pivotal mounting.

Other objects and advantages of my invention will be apparent during the course of the following description.

25 In the accompanying drawings which form a part of this specification and wherein like characters of reference denote like or corresponding parts throughout the same,

Figure 1 is an elevation of a window 30 fitted with my improved screen,

Figure 2 is a vertical sectional view thereof, showing the screen in its raised position,

Figure 3 is a horizontal section through 35 the pivot mechanism,

Figure 4 is a longitudinal section through the pivot actuating and locking mechanism,

Figure 5 is a similar view of a modified form,

40 Figure 6 is a side elevation of the same, Figure 7 is an elevation of the screen, detached,

Figure 8 is a detail perspective showing the key section removed, and illustrating the 45 method of assembling or taking apart,

Figure 9 is a similar view, the keepers and netting being removed,

Figure 10 is a detail section on the line 10—10 of Figure 7,

50 Figure 11 is a similar view on the line 11—11 of Figure 7.

Figure 12 is a plan view of the key section,

55 Figures 13 and 14 are detail views illustrating one mode of assembling the cross-bar, and

Figure 15, is a similar view of another mode of assembling the cross-bar.

In the drawings wherein for the purpose of illustration is shown a preferred embodiment of my invention the numeral 16 designates a window frame of the usual construction which is adapted to receive the screen. This screen comprises side, top, and bottom channel strips 17 which have their 60 sides 18 bent inwardly at an acute angle thereby forming a substantially inverted V-shaped channel with an opening at the top, or apex of the V. These channel strips are adapted to receive substantially V-shaped keepers 19 which fit snugly therein. The outer side 18 of one of the side channel strips is cut away at both of its ends, as at 20, as is the outer side of the bottom channel strip. 70

In assembling, the netting is placed over the inner sides of the channels and the keepers are then slid in place through the cutaway portions 20, and lock the netting in place. The ends of the channel strips are 75 beveled so as to interfit as at 21.

The bottom keeper does not extend beyond the cutaway portion of the channel at one end, in order that the side keeper may be 80 slid in place. The key section 22 is sprung into place over the bottom keeper, and its end is bevelled to interfit with the end of the side keeper. When in this position, the keepers are positively locked in place, and may not be removed without first removing the key section. 85

The keeper strips and key section are provided with openings 23 for the accommodation of a nail 24 or other implement to assist in removing them from the channels. 90

The screen frame is strengthened by means of stay rods 25 which are provided at their ends with head portions 26. The inner sides of the channels are provided with openings of the size of the stay rod, the sides of which are slit as at 27 and struck up at 28 in order to receive the head 26 of the stay rod. When the rods are in place, the struck up portions 28 are pressed back into their original position, as shown in Figure 14, and the rods are locked in position. 100

In the form shown in Figure 15, the large openings 30 open into the smaller openings 31, and when the rod is in position and the netting clamped in place the rod will be securely held. 110

A plate 32 is rigidly secured to the upper

end of the frame and is extended thereabove to be bent upon itself to form a cylindrical sleeve 33 arranged transversely of the screen. Cylindrical pivot bolts 34 are slidably arranged within said sleeve and are adapted to be projected therebeyond by means of studs 35 carried by said bolts and extending through slots 36 in the sleeve. A screw-threaded bolt actuating rod 37 is secured to 5 one of the studs 35, and a similar rod 38 which is not screwthreaded is secured to the other stud, and these rods are connected by an internally screwthreaded coupling member 39. In the form shown in Figure 4, the 10 rod 38 is provided with an enlarged head 40 which engages a recess 41 in the coupling. The coupling member will rotate freely on the rod 38 and will engage the threads on the rod 37 to move the same. It will be seen 15 that rotation of the coupling will project the pivot bolts into the openings 42 and will lock them there until they are retracted by rotation of the coupling member.

In the form shown in Figures 5 and 6, the 20 rod 38 is not positively connected to this coupling but has a reduced portion 43 which extends into the coupling, which abuts against the shoulder 44 formed by the reduced portion. In this form of my invention 25 the coupling only serves to lock the bolts in their extended position. When it is desired to withdraw the pivot bolts, the coupling is screwed onto the rod 37 until the rods fall apart, as in Figure 6, and the bolts 30 may then be manually withdrawn.

A prop or support is formed by the rod 45 which encircles the upper stay rod adjacent one side of the screen and extends nearly to the bottom of the screen where it is bent 40 upon itself to form an eye 46 and then extends back to a point adjacent the stay rod where it is twisted about itself and extended transversely of the screen parallel to the stay rod, about which its free end is twisted adjacent the opposite side of the screen. 45

When it is desired to raise the screen, the eye 46 is hooked over a nail or stud 46' to support the screen in its raised position. It will be seen that the prop will support both 50 sides of the screen and cause it to hang straight although it is arranged nearly entirely on one side of the screen.

A chain 47 or the like is secured to the plate 32 in order that the screen may be 55 hung up in a convenient location when not in use. A hook or catch 48 is secured to the window sill and engages an opening in the lower channel strip to retain the screen in its closed position.

60 While I have shown and described the preferred embodiment of my invention it is to

be understood that various changes in the size, shape, and arrangement of parts may be resorted to without departing from the spirit of my invention or the scope of the 65 subjoined claims.

Having described my invention what I claim as new and desire to protect by Letters Patent is:

1. A screen comprising substantially V- 70 shaped channels, and substantially V-shaped keepers adapted to be slid longitudinally into said channels.

2. A screen comprising substantially V- 75 shaped channels, and substantially V-shaped keepers adapted to be received therein, said channels having certain of their ends provided with cutaway portions to allow insertion of the keepers.

3. A screen comprising substantially V- 80 shaped channels, and substantially V-shaped keepers adapted to be received therein, said channels having certain of their ends provided with cutaway portions to allow insertion of the keepers, one of said keepers terminating short of the channel in which it is 85 received, and a key keeper section adapted to be arranged over said short keeper to complement the same, and lock the keepers in the channels. 90

4. A screen comprising channels, the sides of said channels being inclined towards each other, netting adapted to be arranged over the inner sides of the channels, keepers adapted to be arranged within the channels, certain of the ends of the outer sides of the channels being cut away to allow insertion of the keepers, one of said keepers terminating short of the channel in which it is received, a key keeper section adapted to complement said short keeper and lock all of the keepers in position, stay rods connecting the inner sides of the side channels, and a prop arranged adjacent one side of the screen and engaging both ends of the stay rod to properly support the screen. 100

5. A screen comprising substantially V-shaped channels, substantially V-shaped keepers adapted to be received therein, said channels having certain of their ends provided with cutaway portions to allow insertion of the keepers, one of said keepers terminating short of the channel in which it is received, a key keeper section adapted to be arranged over said short keeper to complement the same and to lock the keepers in the channels, a sleeve secured to the upper channel, pivot bolts slidably arranged in the sleeve, and means to project said bolts and lock the same. 110

In testimony whereof I affix my signature.
WILLIAM N. CROPPER.
